MANUALLY CONTROLLED SOAP PRESS

James Garvey, Vancouver, British Columbia,
Canada

Application October 8, 1948, Serial No. 53,405

10 Claims. (Cl. 25—10)

1

The invention relates to soap presses.

In the production of soap, the final shape, marking and finish are achieved in a soap press, which consists essentially of a fixed die adapted to receive a bar or cake of soap of approximately the desired final dimensions, a moveable die and means for actuating or "tripping" the moveable die so that it will be brought onto the fixed die to exert the desired pressure on the cake of soap. Since the operators of such machines are usually paid according to their production, that is, they are employed as piece workers, they become very skilful in operating a single manually controlled press, in removing the finished cake and inserting another cake to be pressed with a very short interval between the operations of the die, and this skill and speed increase until eventually the operator fails to get his fingers away from the closing die soon enough, and loses one or more fingers.

Automatic machines have therefore been developed to dispense with the services of the operator, but these can only be used where mass production is desired, and further, semi-automatic and fully automatic presses are subject to the disadvantage that they do not provide for variations in pressure and they either cannot provide the dwell at the end of the pressing stroke which is generally considered to be necessary, or may provide it only at very considerable expense. By "dwell" is meant a pause during which the full pressure of the moveable die continues to be exerted instead of being immediately released. Variation in the pressure applied to a cake of soap is desirable because soaps differ in consistency and also in the final density required.

Accordingly single presses attended by an operator are almost universally used and soap manufacturers have sought to provide these presses with controls which would prevent the operators from placing a hand in the danger zone during the closing of the moveable die, the object being so to arrange controls that the moveable die cannot be tripped without the operation of two controls, each requiring a hand. These safety devices have all been subject to the serious disadvantage, however, that it has been possible for the operator to block off one of them so that he can trip the press with one hand instead of both, and thereby increase his production, but eventually lose his fingers.

The principal object of the present invention is to provide a soap press which, because it is manually operated, may be caused to dwell to

2

any extent desired and yet, though it is manually operated, positively cannot be operated without both hands being used to operate controls.

More specifically it is an object of the invention to provide, in a manually operated soap press, control valve means requiring the use of both hands in which no part requiring the use of a hand for operation can be blocked out.

More specifically again it is an object of the invention to provide, in a manually operated soap press, control valve means in which each of two hand operated valves must be actuated at the same time in order to close the moveable die on the fixed die, and must both be released and again actuated before the moveable die can again be caused to close on the fixed die.

A further object of the invention is to provide a soap press in which the moveable die is closed on the fixed die by means of a cylinder and piston assembly operated by a gaseous fluid, preferably air, under pressure.

A still further object of the invention is to provide a soap press in which pressure is applied to a cake of soap by a moveable die closed on a fixed die by means operated by a gaseous fluid under pressure and the duration and degree of this pressure may be varied at will according to the consistency of the soap to be pressed and the final density required.

Other objects and features of the invention will appear from the following description of an embodiment of the invention with reference to the accompanying drawings, in which:

Figure 1 is a front elevation of a soap press according to the invention;

Figure 2 is an elevation of the same press from the right hand side;

Figure 3 is a diagram illustrating the operation of the press;

Figure 4 is an enlarged sectional view of one of the hand operated valves;

Figure 5 is an enlarged sectional view of the shuttle valve;

Figure 6 is a section on the line 6—6 of Figure 5;

Figure 7 is a section on the line 7—7 of Figure 5, and

Figure 8 is a sectional view of the multi-way valve.

Referring to Figures 1 and 2, the soap press is mounted on a frame 10 and includes the conventional fixed die 11, ejector 12 and upper moveable die 13 adapted to be closed on the fixed die 11 to compress a cake of soap placed therein to give it its final shape, marking and fin-

ish. The ejector 12 is operated through piston rod 14 by double acting cylinder and piston assembly 15, the cylinder containing a piston (not shown) which may be operated by the admission of a liquid or a gaseous fluid under pressure, to either end of the cylinder. The upper moveable die 13 is operated through piston rod 16 by double-acting cylinder and piston assembly 17 which may similarly be operated by admission of a liquid or a gaseous fluid under pressure to either end of the cylinder, and a multi-way valve 18 is operable to pass fluid under pressure either to the fluid lines 19 and 20 to withdraw the ejector 12 and move the die 13 to compress a cake of soap against the fixed die 11, or to fluid lines 22 and 23 to withdraw the moveable die 13 and move the piston rod 14 out to raise the ejector 12 in the fixed die 11 and eject the finished cake of soap.

Although as indicated, the assemblies 15 and 17 may be liquid operated, it is desirable that they be of the type operated by a gaseous fluid under pressure and preferably air, so that the only one source of fluid under pressure is required, as indicated in Figure 3. Air under pressure is therefore admitted at 24 to an air filter, regulator, and lubricator indicated generally by the reference numeral 25, and air, at a pressure which may accordingly be regulated as desired in accordance with the consistencies of the soap to be pressed and the final density required, passes from there to the line 26 which is connected to the line 27 leading to the multi-way valve 18 which is provided with an exhaust 28 and a silencer 29.

As illustrated in Figure 8, the multi-way valve 18 is provided with a central bore 30, and a plunger 31 which carries flexible washers 32 and 33, and is moved endwise in the manner described below to one of two positions with the following effect, which may best be understood by reference to Figure 3:

- (1) To pass air under pressure to lines 22 and 23 by connecting inlet 34 to port 35, and to connect lines 19 and 20 to exhaust line 28 by connecting port 36 to exhaust port 37, thus withdrawing the die 13 and actuating the ejector 12 (this being the position shown), or
- (2) To pass air under pressure to lines 19 and 20 by connecting inlet 34 to port 36, and to connect lines 22 and 23 to exhaust line 28 by connecting port 35 to exhaust port 37, thus actuating the die 13 and withdrawing the ejector 12.

The plunger 31 is provided with an extension 31A operating in a chamber 38 separate from the bore 30 and carrying a high pressure cup 39 between washers 40 and 41. Spring 42 engaging washer 41 urges plunger 31 to the position illustrated in Figure 8 in which the inlet 34 is connected to port 35 i. e. the first position described above. The plunger 31 is moved to the second position described above by the admission of air under pressure through inlet 43 which is connected to line 26 by line 44 provided with valve means which make it necessary for an operator to actuate each of two hand operated valves at the same time in order to allow air under pressure to pass through line 44 to inlet 43, and necessary to release both said hand operated valves before the line may be again cleared to operate plunger 31.

This valve means consists of two hand oper-

ated valves A and B illustrated in Figure 4 and a shuttle valve C illustrated in Figure 5. The valves A and B are the same, and in each a plunger 45 (Figure 4) is urged by a spring 46 to the position illustrated in which the connection 47 to the high pressure side of the valve is closed off by the plunger 45, and the connection 48 which is on the low pressure side of the valve in the line 44 is connected to exhaust. Therefore, referring to Figure 3, the valve A normally exhausts the portion of line 44 between valve A and valve C, while preventing air under pressure from passing to valve C, and valve B similarly exhausts the portion of line 44 between valve B and inlet 43 of the multi-way valve 18 while preventing the passage to the inlet 43 of any air under pressure which might be passed by valve C. When the plunger 45 of valve A is pressed down, the port 49 is brought into line with the connections 47 and 48, and air under pressure then passes to the shuttle valve C (Figure 5) entering at 50 and passing from outlet 51, if, as explained below, valve B is also operated at the same time as valve A.

Valve C has a casing 52 which, for convenience in assembling the valve, is formed with a central piece 53, an inlet end piece 54 and an outlet end piece 55. The central piece is divided into two chambers X and Y by a fixed wall 56, and the chamber Y is separated from the chamber Z formed in the end piece 55 by a plug 57 having formed therethrough a central passage 58 adapted to be blocked on the outlet side by a check valve 59.

Referring to Figures 5, 6 and 7, the end of the check valve which abuts the plug 57 is formed with cut-outs 60 (Figure 7) and is guided on the inner face of the end piece 55 while the other end of the check valve is guided by the inturned flange 61 of an insert 62 (Figures 5 and 6), the flange being provided with holes 63.

A hollow plunger 64 extends from the chamber Y through a suitable aperture in the fixed wall 56 and through a seal 65 into the chamber Y, the end of the plunger extending into chamber Y being provided with holes 66, referred to below, and the other end carrying a high pressure cup 67. A tube 68 fixed to a base 69 is positioned within the hollow plunger 64 and extends to a point close to the holes 66 so that air entering valve C at 50 is at once conveyed to holes 66 and thus to chamber Y. The tube 68 is however, spaced from the hollow plunger 64 to define an annular passage 70 through which air may also pass to the portion of chamber X between the high pressure cup 67 and the base 69 of the tube 68. A spring 71 normally holds the plunger 64 in the position shown in Figure 5.

The end wall of the plunger 64 adjacent the holes 66 is closed, as illustrated and is adapted to close off the passage 58 when the plunger 64 is moved to the left in Figure 5 against the action of spring 71. During such movement a build-up of pressure in the chamber X between the high pressure cup and the fixed wall 56 is prevented by vent 72.

As will appear from the description which follows, the check valve 59 is left, at the end of a complete operation of the moveable die 13, in the seated position blocking the passage 58 and will remain in that position until the valve B is operated. It is therefore necessary that both valves A and B be operated but when they are, the check valve 59 is unseated and air under pressure passes through the outlet 51 to the

valve B and from there through the balance of the line 44 to the inlet 43 of multi-way valve 18 (Figure 8), so as to move the plunger 31 and its extension 31A downwardly to withdraw the ejector 12 and move the die 13 to compress a cake of soap placed in the die 11. The pressure exerted by the die 13 may be maintained for any length of time desired to provide the dwell referred to herein, and on release of the two valves A and B the line 44 is exhausted and the spring 42 is enabled to return the plunger 31 to the position shown in Figure 8, in which the die 13 is withdrawn and the ejector 12 is actuated.

When the plunger 31 has been moved, against the action of the spring 42, to the second position referred to above (i. e. the opposite of the position shown in Figure 8), the pressure in the line 44 quickly builds up until it is the same at the inlet 43 and at both ends of passage 58. Accordingly the pressure builds up in the chamber Y. During this build-up of pressure air has, of course, passed through the annular passage 70 to the portion of chamber X between the high pressure cup 67 and the base 69 of tube 68, and when there is no longer any flow of air through the passage 58 the plunger 64 is moved to the left in Figure 5 by reason of the pressure exerted on the cup 67. The space between the cup 67 and base 69 thus increases and there is momentarily a drop in pressure in the chamber Y. This momentary pressure drop allows the pressure in the chamber Z to seat the check valve 59 in the plug 57. Plunger 64 then continues to move until it closes passage 58, thus preventing further air under pressure from passing to valve B. The plunger 64 cannot be retracted until the pressure at the inlet 50 is released and therefore valve A must be released so as to exhaust the line between valves A and C before plunger 64 can be moved clear of passage 58. It is apparent therefore that the valve A cannot be tied down, but instead must be released and actuated again before a fresh slug of air may be passed through the shuttle valve C. Similarly, the valve B may not be tied down but must be actuated at the same time as valve A and must thereafter be released again before shuttle valve C will pass more air under pressure. If valve B were held down, the pressure in the line between outlet 51 of valve C and inlet 43 of valve 18 would hold the check valve 59 on its seat and prevent the passage of air through passage 58. In order to enable air passed by valve A to get to inlet 43 (Figure 8), check valve 59 must be moved from its seat and to this end valve B must be released to exhaust the line between it and inlet 43 and must be again actuated to connect the line between valves C and B to the remainder of the line leading to inlet 43. It will be observed that it is necessary that the valves A and B be operated at the same time because if valve B is not operated at the same time, check valve 59 remains on its seat and air under pressure promptly passes through passage 58 to chamber X and moves plunger 64 to close off passage 58. It is therefore impossible for an operator to cause the die 13 to move towards the die 11 without using both hands to actuate the two valves A and B and to release them.

It will be apparent that because the machine is manually operated it satisfies not only those who prefer the dwell mentioned above, but those who consider that a better result is obtained by two or more sharp strokes of the die, a modification of the press being contemplated which will pro-

vide for two or more such strokes at one operation of the controls.

While in the embodiment of the invention described above the multi-way valve 18 is connected to close the moveable die 13 on the fixed die 11 when the plunger 31 is moved against spring 42 and to withdraw the moveable die 13 when the line 44 is exhausted, the connections may be reversed so that when the plunger 31 is in the position illustrated in Figure 8, the moveable die 13 is closed on the fixed die 11 and movement of the plunger 31 on the admission of air under pressure to chamber 38 has the effect of withdrawing the moveable die 13. In that event the hand operated valves A and B must be modified so that when they are released the port 49 is brought into line with the connections 47 and 48, and when they are operated the connection 47 to the high pressure side of the line is closed off and the connection 48 is connected to exhaust.

I claim:

1. In a manually controlled soap press of the type having a fixed die adapted to receive a cake of soap, a moveable die adapted to close thereon to compress the cake of soap, a fluid-operated double acting cylinder and piston assembly, and a multi-way valve operable to connect fluid under pressure to said assembly to move the moveable die to open and closed positions, an improved safety operating arrangement comprising means normally holding the multi-way valve in position to connect said cylinder and piston assembly to move the moveable die to one of said positions, means operable by a gaseous fluid under pressure and adapted in response to a given pressure to actuate the multi-way valve to connect said cylinder and piston assembly to move the moveable die to the other of said positions, a line connecting the last mentioned means to a source of gaseous fluid under pressure, safety valve means in said line comprising, two hand operated valves, each adapted in a first position to interrupt the line and exhaust the same on the low pressure side of each hand operated valve, and in a second position to open the line, and, between the hand operated valves, valve means adapted on actuation of the multi-way valve and equalization of pressure in the line, to close the line and maintain the same closed until the hand operated valves are both returned to said first position.

2. In a manually controlled soap press of the type having a fixed die adapted to receive a cake of soap, a moveable die adapted to close thereon to compress the cake of soap, a fluid-operated double acting cylinder and piston assembly, and a multi-way valve operable to connect fluid under pressure to said assembly to move the moveable die to open and closed positions, an improved safety operating arrangement comprising means normally holding the multi-way valve in position to connect said cylinder and piston assembly to move the moveable die to one of said positions, means operable by a gaseous fluid under pressure and adapted in response to a given pressure to actuate the multi-way valve to connect said cylinder and piston assembly to move the moveable die to the other of said positions, a line connecting said last mentioned means to a source of gaseous fluid under regulated pressure, safety valve means in the line comprising, two hand operated valves, each adapted in a first position to interrupt the line and exhaust the same on the low pressure side of each hand operated valve, and in a second position to open the line, and, between the hand operated valves, valve means comprising

ing a casing having an inlet and an outlet, means dividing the casing into at least two chambers, a passage connecting said two chambers, a check valve in the chamber on the outlet side of said passage operable to close the same, and a valve moveable in the chamber on the inlet side of said passage and operable on equalization of pressure in the line between said passage and said multi-way valve first to create a drop in pressure in the chamber on the inlet side of said passage adapted to seat the check valve and thereafter to close said passage.

3. In a manually controlled soap press of the type having a fixed die adapted to receive a cake of soap, a moveable die adapted to close thereon to compress the cake of soap, a fluid-operated double acting cylinder and piston assembly, and a multi-way valve operable to connect fluid under pressure to said assembly to move the moveable die to open and closed positions, an improved safety operating arrangement comprising means normally holding the multi-way valve in position to connect said cylinder and piston assembly to move the moveable die to one of said positions, means operable by a gaseous fluid under pressure and adapted in response to a given pressure to actuate the multi-way valve to connect said cylinder and piston assembly to move the moveable die to the other of said positions, a line connecting said last mentioned means to a source of gaseous fluid under regulated pressure, safety valve means in the line comprising, two hand operated valves, each adapted in a first position to interrupt the line and exhaust the same on the low pressure side of each hand operated valve, and in a second position to open the line, and, between the hand operated valves, valve means comprising a casing having an inlet and an outlet, means dividing the casing into at least two chambers, one in communication with said outlet and another with said inlet, a passage connecting said two chambers, a check valve in the outlet chamber operable to close said passage, a plunger having means at the end remote from said passage adapted in response to pressure to move the plunger longitudinally to close said passage at the inlet chamber side, and a passage adapted to pass the gaseous fluid at the pressure existing in the inlet chamber to said pressure means.

4. In a manually controlled soap press of the type having a fixed die adapted to receive a cake of soap, a moveable die adapted to close thereon to compress the cake of soap, a fluid-operated double acting cylinder and piston assembly, and a multi-way valve operable to connect fluid under pressure to said assembly to move the moveable die to open and closed position, an improved safety operating arrangement comprising means normally holding the multi-way valve in position to connect said cylinder and piston assembly to move the moveable die to one of said positions, means operable by a gaseous fluid under pressure and adapted in response to a given pressure to actuate the multi-way valve to connect said cylinder and piston assembly to move the moveable die to the other of said positions, a line connecting said last mentioned means to a source of gaseous fluid under regulated pressure, safety valve means in the line comprising, two hand operated valves, each adapted in a first position to interrupt the line and exhaust the same on the low pressure side of each hand operated valve, and in a second position to open the line, and, between the hand operated valves, valve means comprising a casing having an inlet and an outlet, means dividing

the casing into three chambers, one in communication with said outlet, a main inlet chamber in communication with said inlet and a subsidiary inlet chamber in communication with the main inlet chamber, a passage connecting the outlet chamber and the main inlet chamber, a check valve in the outlet chamber operable to close said passage, a plunger moveable to close said passage at the inlet chamber side, and means in said subsidiary inlet chamber connected to the plunger and adapted in response to a given pressure of the gaseous fluid admitted to the subsidiary inlet chamber, to move the plunger to close said passage.

5. In a manually controlled soap press of the type having a fixed die adapted to receive a cake of soap, a moveable die adapted to close thereon to compress the cake of soap, a pneumatic double acting cylinder and piston assembly, and a multi-way valve operable to connect air under pressure to one end or the other of said assembly, means normally holding the multi-way valve in position to connect air to said assembly to withdraw the moveable die, an improved safety operating arrangement comprising means operable by air under pressure and adapted in response to a given pressure to actuate the multi-way valve to pass air to said assembly to close the moveable die on the fixed die, a source of air under regulated pressure, a line connecting said source to the inlet of the multi-way valve, a line connecting said source to said means operable to actuate the multi-way valve, safety valve means in the last mentioned line comprising two hand operated valves each adapted normally to interrupt the line and exhaust the same on the low pressure side of each hand operated valve, and when operated to open the line, valve means between the hand operated valves and comprising a casing having an inlet and an outlet, means dividing the casing into three chambers, one in communication with said outlet, a main inlet chamber in communication with said inlet and a subsidiary inlet chamber in communication with the main inlet chamber, a passage connecting the outlet chamber and the main inlet chamber, a check valve in the outlet chamber operable to close said passage, a hollow plunger mounted in said inlet chamber and moveable longitudinally to close said passage at the inlet chamber side, a high pressure cup connected to the plunger and positioned in the subsidiary inlet chamber, a tube within the hollow plunger adapted to pass air under pressure from said inlet to the main inlet chamber, an annular passage formed between the plunger and the tube connecting the main inlet chamber to the subsidiary inlet chamber on the side of the high pressure cup remote from the main inlet chamber, and spring means of a given strength acting on said plunger to resist movement in the direction to close said passage.

6. In a manually controlled soap press of the type having a fixed die, a cooperating ejector, and a moveable die, the combination of control means having a position for causing closing of the moveable die on the fixed die and withdrawal of the ejector and a position for causing withdrawal of the moveable die and actuation of the ejector, means normally holding the first mentioned means in one position, and pressure operated means for moving the first mentioned means to the other position; a line connecting said pressure operated means to a source of gaseous fluid under pressure, and, in said line, safety valve means comprising two hand operated valves

each adapted in a first position to interrupt the line and exhaust the same on the low pressure side of each hand operated valve and in a second position to open the line, and, between the hand operated valves, valve means adapted, on operation of the pressure operated means and equalization of pressure in the line, to close the line and maintain the same closed until the hand operated valves are both returned to said first position.

7. In a manually controlled soap press of the type having a fixed die, a cooperating ejector, and a moveable die, the combination of control means having a position for causing closing of the moveable die on the fixed die and withdrawal of the ejector and a position in which it causes withdrawal of the moveable die and actuation of the ejector, means normally holding the first mentioned means in one position, and pressure operated means for moving the first mentioned means to the other position; a line connecting said pressure operated means to a source of gaseous fluid under pressure, and, in said line, safety valve means comprising two hand operated valves each adapted in a first position to interrupt the line and exhaust the same on the low pressure side of each hand operated valve and in a second position to open the line, and, between the hand operated valves, valve means comprising a casing having an inlet and an outlet, means dividing the casing into three chambers, one in communication with said outlet, a main inlet chamber in communication with said inlet and a subsidiary inlet chamber in communication with the main inlet chamber, a passage connecting the outlet chamber and the main inlet chamber, a check valve in the outlet chamber operable to close said passage, a plunger moveable to close said passage at the inlet chamber side, and means in said subsidiary inlet chamber connected to the plunger and adapted in response to a given pressure of the gaseous fluid admitted to the subsidiary inlet chamber, to move the plunger to close said passage.

8. A soap press comprising a fixed die, a moveable die adapted to close thereon to compress a cake of soap, a double-acting cylinder and piston assembly operated by a gaseous fluid under pressure, a multi-way valve operable to connect a source of gaseous fluid under pressure to said assembly to move the moveable die either to open

or to closed position, and means for operating the multi-way valve.

9. A manually-controlled soap press comprising a fixed die, a moveable die adapted to close thereon to compress a cake of soap, a double-acting cylinder and piston assembly operated by a gaseous fluid under pressure, a multi-way valve operable to connect a source of gaseous fluid under pressure to said assembly to move the moveable die either to open or to closed position, means for regulating the pressure of said gaseous fluid admitted to said cylinder and piston assembly, and manually-controlled means for operating the multi-way valve.

10. A manually-controlled soap press comprising a fixed die, a moveable die adapted to close thereon to compress a cake of soap, a double-acting cylinder and piston assembly operated by a gaseous fluid under pressure, a multi-way valve operable to connect a source of gaseous fluid under pressure to said assembly to move the moveable die either to open or to closed position, means for regulating the pressure of said gaseous fluid admitted to said cylinder and piston assembly, means normally holding the multi-way valve in position to connect said cylinder and piston assembly to move the moveable die to one of said positions, means operable by a gaseous fluid under pressure and adapted in response to a given pressure to actuate the multi-way valve to connect said cylinder and piston assembly to move the moveable die to the other of said positions, a line connecting said last-mentioned means to a source of gaseous fluid under pressure and valve means in the line adapted in a first position to interrupt the line and exhaust the same on the low pressure side thereof and in a second position to open the line whereby to operate said pressure-responsive means to actuate the multi-way valve.
